WRITING MACHINE ATTACHMENT

Raymond Dow, Flushing, N. Y.

Application March 3, 1939, Serial No. 259,505

5 Claims. (Cl. 197—187)

This invention relates to margin and sheet edge indicators for use in connection with writing machines and has as its principal object the provision of such a device that can be applied to 5 existing machines or can be built into new machines without necessitating the cutting, grooving or channeling of the platen as is commonly necessary in devices of this kind heretofore proposed.

A further object of the invention is to provide a 10 combination sheet edge indicator and right hand margin indicator, the sheet edge indicator operation being such that, without attention on the part of the operator of the writing machine, the approaching bottom edge of the sheet will be 15 audibly indicated or the platen will be locked against further line spacing movement. The right hand writing margin will be indicated automatically and audibly to give the operator ample warning so that the typing can be properly terminated to provide a neat even margin down the sheet, the mechanism for doing this being adjustable so that the width of the sheet and the relative position of the margin edge will be compensated for, the mechanism being universal.

A still further object of the invention is to 20 provide a mechanism of the character referred to which is simple of construction, fool-proof in operation, can be applied to the machine at minimum cost and needs no instruction for the operator to understand the setting of the page end and right margin indicator. The mechanism may 25 provide for an audible or visible signalling means as desired and may be applied to bookkeeping, billing or other business machines.

Changes and variations may be made in the 30 construction shown and described without departing from the principles of the invention or sacrificing its chief advantages; hence such invention is not to be restricted to the precise structures shown in the drawing, in which:

Figure 1 is a view in side elevation of the 35 carriage portion of a writing machine, some parts being broken for clarity of illustration, showing the page end indicator and margin indicator in 40 the positions they occupy when both are in position ready for operation.

Figure 2 is a view similar to Figure 1 showing 45 the positions occupied by both indicators after operation or after the edge of the paper has disengaged said indicators.

Figure 3 is a view in front elevational section, 50 the section being taken on the line 3—3 of Figure 2, the operating parts of both indicators being shown, and

Figure 4 is a view similar to Figure 2 showing

a modified form of bottom edge indicator in which the platen is locked against further line space movement when the paper leaves the gauge arm.

Figure 5 is a view in elevation of a modified 5 form of margin indicator that is compact and moves with the carriage when the latter extends to the right.

Referring to the drawing in detail, 10 indicates a writing machine, which term embraces all machines upon which characters are printed on paper by a manually operated machine. The machine includes a carriage 11 mounted for reciprocal movement on the rails 12 and carrying a revolvable platen 13 mounted in the sides 14 15 and 15 of the carriage on the shaft 16. The carriage 11 further provides the usual paper guide 17 which surrounds the lower, front and rear portions of the platen to guide the paper 18 thereabout. The cooperation of the platen and its 20 companion feed rolls 19 moves the paper vertically to space lines of writing by suitable platen line-spacing mechanism, not shown, but common in writing machines. Suitable mechanism, not shown, is also a part of the machine to provide 25 for the lateral movement of the carriage as the writing progresses, so that writing without thought on the part of the operator could continue off the right hand margin of the paper 18.

In order to warn the operator of the machine 30 that the end of a line is approaching, I employ a gauge finger 20 having a hammer portion 21 and pivoted as at 22 to a supporting device as shown in Figure 5, of adjustable character comprising the bell 23, support arm 24, and telescopic 35 holder 25 in which the arm 24 is attached, the holder being mounted as at 26 to any convenient part of the stationary machine frame 27. The gauge end 28 of arm 20 is slightly curved and lies in a trough or channel 30 provided in the bottom 40 of the paper guide 17 beneath the platen and extending from side 14 to side 15, through the latter of which the finger 20 extends. As the paper is fed down the paper guide behind the platen, it lifts the finger 20, the latter being light, and in 45 cross section being curved from its top edge down, to cause the paper to pass thereunder. The paper beneath the platen conforming to the bellied drop of the paper guide beneath and away from the under side of the platen forms a space 31 with 50 which the channel 30 combines to form a spacing for the end of the finger 20 so that it can drop from its supported position as illustrated in Figure 1 to the position shown in Figure 2, as it rides off the right hand edge of the paper and drops 55

- into the channel to cause the hammer end 21 to ring the bell to warn the operator that the line is nearing the edge of the paper or approaching the set margin. It is understood that in Figure 5, 5 the operator sets the finger by moving it relatively to the carriage and paper therein through the medium of the telescopic construction of the supporting device, and the adjustable stop 24A on arm 24.
- 10 In order that the bottom of the page of typing may be accurately determined in advance, I provide a yoke strip 33 which in its side arm portions 34 is pivoted as at 35 and 36 to the sides of the carriage. The yoke strip is free to swing in the 15 space beneath the platen and is moved with and by the paper as it passes beneath the platen and is held or wedged in the position shown in Figure 1 by the paper, the bottom edge of said strip engaging the paper so that as the bottom edge of 20 the paper draws out from under the bottom edge of the strip, the strip is free and drops by its weight to the position shown in Figure 2, at which time the hammer 37 on an extended arm portion 38 of the yoke strip rings the bell 39 to provide an 25 audible signal to warn the operator that a new page should be started.
- The page end indicator yoke strip 33 is automatically actuated by insertion of a sheet of paper. Should it become necessary to raise the 30 margin finger 20 to insert it above the paper, it can be manipulated by pulling down the hammer to raise the gauge finger.
- In some cases it may be desirable to lock the platen against rotation when the paper releases 35 the yoke strip and to this end I have provided a yoke strip (Figure 4) with a ratchet dog 40 which is arranged to engage the ratchet teeth 41 of a gear 42 attached to one end of the platen. As the paper is used in typing, the lower edge 40 will ride from under the edge of the yoke strip and release the same, which, by its weight will drop down to the full line position in Figure 4 and cause engagement of the dog with the ratchet teeth to stop rotation of the platen.
- 45 It is evident that in both page end and line end indicators, the mechanisms can be incorporated in typewriters or bookkeeping machines or any number or letter handling machines without cutting the platen or without the addition 50 of a multiplicity of complicated parts that require expert manipulation for operation and setting. The fixed gauge 20 as shown in Figure 3, has its support arm 20A squared at 27A to fit into the holder 27B mounted on part 27 of the frame, the arm 20A being long enough, as is arm 20, to allow for the full movement of the carriage to the 55 right. In Figure 5, the telescopic means allows the gauge to be moved by and with the carriage and returned with it under the influence of spring 60 24B. Adjustment of both types is provided for. The finger 45 on Fig. 4 yoke releases the dog 40. The line end indicator, or side margin gauge also functions as a page end indicator in that it will cease to function as a side margin indicator and 65 thus warn the operator that the end of the paper has been reached. It is a combination side and end margin indicator. While I have illustrated and described my invention with some degree of particularity, I realize that in practice various 70 alterations therein may be made without depart-

ing from the spirit of the invention or the scope of the appended claims.

What I claim is:

1. In a writing machine, in combination, a stationary frame, a movable carriage in the frame including, a platen, a paper guide passing under said platen and having a longitudinal channel therein, a side margin-gauge mounted on the frame and having an arm disposed between said guide and the platen and normally held out of the channel by paper passing about said platen and a signal actuated by said margin gauge arm as the latter drops into the channel as one side edge and the lower edge of the paper moves from thereunder as the writing progresses. 15

2. In a writing machine, in combination, a stationary frame, a movable carriage in the frame including a platen and a paper guide beneath the platen, said guide being shaped to provide a channel extending longitudinally beneath the 20 platen, a gauge arm pivoted to said frame and arranged to be held out of the channel by paper passing about the platen, said arm riding off one side and lower marginal edges of the paper to indicate a side margin position and the lower 25 end of the paper, and a signal actuated by the drop of the arm into the channel as it leaves the edge of the paper.

3. In a writing machine, in combination, a stationary frame, a movable carriage in the frame 30 including, a platen, a paper guide under the platen having a longitudinal channel therein, a margin-gauge arm pivoted to the frame and having an end disposed between said guide and the platen and normally held out of the channel 35 by paper passing about the platen, a signal actuated by the arm as the latter drops into the channel as the side edge of the paper moves from thereunder, and means for adjusting said arm relatively to said frame to vary the margin 40 indicating signal in accordance with the width of side edge margin desired.

4. In a writing machine, in combination, a stationary frame, a movable carriage in the frame including, a platen, a paper guide passing under said platen and having a longitudinal channel therein, a margin gauge arm mounted on the frame and having a portion disposed between said guide and the platen and normally held out of the channel by paper passing about 50 said platen and a signal actuated by said margin gauge arm as the latter drops into the channel as either one side or the bottom edge of the paper moves from thereunder as the writing progresses.

5. In a writing machine, in combination, a 55 stationary frame, a movable carriage in the frame including, a platen, a paper guide passing under said platen and having a longitudinal channel therein, a pivoted margin gauge arm mounted on the frame and having a portion disposed between said guide and the platen and normally held out of the channel by paper passing about 60 said platen and a signal actuated by said margin gauge arm as the latter drops into the channel as the paper moves from thereunder as the writing progresses, and means for adjusting said arm to vary the margin indicating signal in accordance with the width of margin desired. 65
